[57] CLAIM

The ornamental design for flexible board for a game or similar article, as shown and described.

DESCRIPTION

FIG. 1 is a front elevational view of flexible board for a game showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and

FIG. 7 is a perspective view thereof;

FIG. 8 is a right side elevational view of said design of the same embodiment in its folded position;

FIG. 9 is a left side elevational view thereof;

FIG. 10 is a front elevational view thereof; and

FIG. 11 is a perspective view thereof.
